UNITED STATES PATENT OFFICE

WALTER S. EPPLEY, OF YORK, PENNSYLVANIA

FLUID-OPERATED MECHANISM FOR RAILWAY SWITCHES

Application filed August 20, 1929. Serial No. 387,215.

This invention relates to improvements in fluid-operated switch mechanism for railway switches and is especially adapted for the operation of street railway switches from cars 5 of electric railways.

One object of the invention is to provide an improved mechanism, connected with the switch-bar, by which the latter may be operated by fluid pressure and thereby avoid the 10 use of solenoids and coils and the expense of maintaining the same together with their operating objections.

Another object is to provide an improved fluid-pressure switch-operating mechanism 15 which will operate the switch-bar positively in both directions and which will avoid throwing the point in either direction with a snap and also avoid the splashing of water as the point reaches its limit of movement.

20 A further object is to provide an improved fluid-pressure switch-operating mechanism by which the operating pressure may be varied to suit the particular switch-bar to which it is connected and thereby permit the heel of the 25 switch-bar to be kept tight to prevent rocking of the same and avoid derailment of the vehicle.

A still further object is to provide an improved fluid-pressure switch-operated mechanism 30 which shall be extremely simple in construction and which may be operated at an extremely low maintenance cost.

With these, and other objects in view, the 35 invention is illustrated in the accompanying drawings wherein,—

Fig. 1 shows the apparatus in the trackway casing with the cover of the latter removed and in top view.

Fig. 2 illustrates the fluid-pressure mechanism in front elevation with a portion of the 40 casing in vertical section.

Fig. 3 shows the fluid-pressure mechanism in end elevation and a portion of the casing in vertical section, as viewed on the line 3-3 of 45 Fig. 1.

Fig. 4 illustrates the same as viewed on the line 4-4 of Fig. 1, and

Fig. 5 shows the switch in vertical section 50 and the casing containing the operating mechanism at the side thereof.

Referring to the drawings, the numeral 10 designates a metal box or casing having a bottom 11; side walls 12 and 13; end walls 14 and 15 and a crosswise partition 16 which divides the interior of the casing into two 55 compartments.

A horizontal flange 17 extends all the way around the top edge of the casing and is provided with bolt-holes 18 so that a cover may be seated upon said flange with an interposed gasket, and the cover then bolted down to seal the casing and its two compartments against the entrance of water and dirt.

In one of the casing compartments, I place 60 an electric motor 19 which is so designed and wired that it may be rotated in either of two directions according to the completion of electric-circuits through its connections. Obviously I make no claim to any structural features of the motor as any motor capable of reversals in its operation will answer my purpose.

In the other of the two compartments, I provide my improved fluid-pressure devices 65 which will now be explained.

70 The fluid-pressure devices are all assembled and mounted on a base 20 which latter is provided with two spaced-apart vertically-extending blocks 21. Each of these blocks supports a cylinder-head 22 and each head is provided, in this instance, with a horizontal base flange 23, which seats and is bolted down on top of its block,—bolts 24 being utilized for this purpose.

75 The two heads therefore extend vertically above the blocks but in spaced relation so that a cylinder 25, may be inserted horizontally between the heads and held clamped therebetween so that a tight joint between the heads and the opposite ends of the cylinder 80 will be effected.

The longitudinal axis of the cylinder 25, therefore extends in a horizontal direction.

A piston 27, shown in broken lines in Figs. 95 1 and 2, is located in the cylinder 25, and has a stem 28, which extends through one of the heads 22 and passes through a stuffing box 29, which effects a tight joint about said stem.

At one end of the cylinder 25, there is a 100

pipe 30 opening into the interior through one head 22, and said pipe leads to and has connection with one side of a rotary pump 31 and said pipe has a vertical extension 32, with an intake valve 33 at the lower end thereof. A relief-valve 34 is also provided in the extension 32, so that when the pressure in the pipes 30 and 32 reaches a predetermined point the valve 34 will open and vent said pipes.

At the opposite end of the cylinder 25, there is another pipe 35 extending through the other head 22 and this latter pipe 35 leads to the opposite side of the rotary pump 31 and also has a depending extension 36 with an intake valve 37 therein. A relief or check valve 38 is also attached to the pipes 35 and 36 to vent pressure in excess of a predetermined amount from said pipes.

Both intake valves 33 and 37 are adjustable as are also the relief valves 34 and 38.

In practice, the compartment containing the cylinder and pump will be supplied with oil and both of the valves 33 and 37 will be submerged in such oil for a purpose that will presently be explained.

The rotary pump 31, has a single shaft 39 extending horizontally therefrom by which the pump may be operated and the pump is of a well-known form and capable of operation in either direction of rotation of its shaft.

By this means, if the pump-shaft 39, is rotated in one direction, oil will be drawn through one of the valves 33 or 37 and into one side of the pump and then forced out from the opposite side of the pump into pipes 30 or 35, as the case may be, and delivered under pressure to one or the other end of the cylinder 25.

If, for example, the pump be operated to draw oil through valve 33 and pipes 32 and 30 into the one side of the pump and then force it out through the opposite side of said pump, the forced oil will be driven through pipe 35, into the cylinder 25, and force the piston 27, from the right to the left end of that cylinder and thereby retract the stem 28. During this operation, the oil in the cylinder at the rear of the piston, will be drawn out by the pump and very little, if any, oil will have to pass through the check valve 33 so that the valves 33 and 37 simply operate to keep the system supplied with oil, because a quantity of oil is exhausted from the cylinder at one side of the piston and passed through the pump and then forced into the cylinder at the opposite side of the piston.

If however, the piston is moved over by incoming oil and the pump continues to operate for a short period, then the surplus oil will be forced out through the relief valve on the charging side of the cylinder.

The piston-stem 28, is connected to a rod

40, which latter extends through the wall 15 of the casing and connects with the switch-bar in the usual way so that when the piston 27 is moved in one direction, the switch-bar will be thrown in a corresponding direction.

The operation of the pump 31 controls the direction of movement of the piston, its stem and the switch-bar, while the pump-operation is controlled by a motor 41 located in the other compartment of the casing 10 which motor may also be operated in either direction.

I provide a flexible connecting member 42 between the shaft of the motor and the pump-shaft 39 which connection extends through an opening in the partition 16 of the casing.

The motor is provided with binding posts 43, 44, 45 and 46 respectively to which wires are attached and the wiring is such that the motor may be operated or revolved in either of two directions.

The means for controlling the circuits to the motor to effect its rotation in either direction forms no part of the present invention, but is to form the subject of a separate application for patent.

This control means is located on a pole or support adjacent to the switch and is preferably operated through connections formed via the trolley wire by manipulation of the controller lever on the car by the motorman.

The casing, containing the motor in one compartment and the pump and piston mechanism in the other compartment in which latter oil is poured to a depth at least sufficient to completely submerge the intake valves 33 and 37, is placed in the roadbed between the track-rails and at the switch-blade and the piston stem 28 is connected with the switch-blade by a rod 40.

The wire connections from the control means to the motor are made and the casing may then be sealed by a cover for an indefinite period of time as practically no attention to the mechanisms in the casing is required for months.

The operation of the device is exceedingly simple and complete and its control is effected by the motorman on the car through the manipulation of the controller so as to either close or leave open the circuit to the motor. This however, forms no part of the present invention and need not be described or explained herein.

Having described my invention, I claim,—

1. In a railway switch-operating mechanism the combination with a cylinder, of a fluid-operated piston in said cylinder, said piston having a stem for connection with a railway switch-bar, a reversible rotary pump, always open pipe-connections direct from one side of the pump to one side of the piston in said cylinder, always open pipe-connections direct from the other side at the revers-

ible rotary pump to the opposite side of the piston in said cylinder whereby the pump itself will be the only intervening thing in the connections between the two sides of the piston, and means for rotating the pump in either direction and cause it to draw fluid from one side of the piston while it supplies fluid to the opposite side of the piston.

2. In a railway switch-operated mechanism the combination with a railway switch-bar, of a casing having a compartment with a fluid therein, a cylinder in said compartment, a fluid-operated piston in said cylinder, said piston having a stem connected to the said switch-bar, a pump in said fluid compartment, pipe connections from one side of the pump to one side of the piston in said cylinder, said connections having an extension with a check-valved inlet submerged in the fluid of said compartment, pipe connections from the other side of the pump to the opposite side of the piston in said cylinder, said latter connections also having an extension with a check-valved inlet that is also submerged in the fluid of said compartment and reversible means for operating the pump in either of two directions to draw fluid from one of the pipe connections and from one side of the piston to and through the pump and force said fluid through the other connections to the opposite side of the piston.

3. In a railway switch-operating mechanism the combination with a cylinder, of a fluid-operated piston in the cylinder, said piston having a stem for connection with a switch-bar, a pump having two connections, piping establishing continuous communication between one of the pump-connections and one side of the piston in said cylinder, separate piping establishing continuous communication between the other of said pump-connections and the opposite side of the piston in said cylinder and means for operating the pump in either of two directions to draw fluid direct from one side of the piston and force it direct to the opposite side of said piston.

In testimony whereof I affix my signature.
WALTER S. EPPLER.
